UNITED STATES PATENT OFFICE.

GEORGE J. MACLAUGHLIN AND JAY L. WILLARD, OF ROCHESTER, NEW YORK,
ASSIGNORS TO PULLMAN MANUFACTURING COMPANY, OF ROCHESTER, NEW
YORK, A CORPORATION OF NEW YORK.

SPRING SASH-BALANCE.

1,082,034.

Specification of Letters Patent. Patented Dec. 23, 1913.

Application filed February 19, 1913. Serial No. 749,558.

To all whom it may concern:

Be it known that we, GEORGE J. MACLAUGHLIN and JAY L. WILLARD, citizens of the United States, and residents of Rochester, in the county of Monroe and State of New York, have invented certain new and useful Improvements in Spring Sash-Balances, of which the following is a specification.

10 This invention relates to sash-balances of the type in which a coiled spring is employed to actuate a pulley, upon which is wound a band or cord connected with the window-sash.

15 The object of the invention is to produce a sash-balance of the type in question having a novel and simple construction and arrangement by which the operation of the device is improved, and its manufacture simplified, particularly by facilitating the employment of a sheet-metal construction of the parts in place of the cast construction heretofore employed.

20 To this end the invention consists in the construction and arrangement of parts hereinafter described, as they are defined in the succeeding claim.

25 In the accompanying drawings:—Figure 1 is a sectional elevation of a sash-balance embodying the present invention, on a central plane normal to the axis of the pulley; Fig. 2 is a section on the line 2—2 in Fig. 1; and Fig. 3 is a side-elevation, looking from the left in Fig. 2, showing in detail the 30 pulley-casing, the pulley, and the pivot-member in their operative relation.

35 The invention is illustrated as embodied in a sash-balance of which all of the principal parts are constructed of sheet-metal, the balance being of the type which is seated in a mortise in the side of the window-frame. The illustrated balance has the usual face-plate 5, which is screwed against the inner surface of the window-frame, and which has 40 lateral ears 6, bent backwardly so as to extend into the mortise and provide supports for the other parts of the mechanism. The ears 6 embrace the pulley-casing, which comprises a side-wall 7, and a flange 8 which 45 incloses the periphery of the pulley. The pulley is stamped of a single piece of sheet-metal and comprises a web-portion 9, a rim 10, and an intermediate flange 11. The 50 flexible member by which the pulley is con-

55 nected with the window-sash is in the form of the usual metal ribbon or band 12, which is wound upon the rim 10 of the pulley and looped at one end, as shown in Fig. 1, through openings in the rim of the pulley, being thus fastened thereto. The coiled 60 spring 13 is of the usual form, having one end 14 fastened to the rim of the pulley, while its inner end is fastened to the central pivot-member.

65 The novelty of the present invention resides particularly in the construction of the central pivot-member 15. This member, as shown in the drawings, comprises a cylindrical body which is slotted longitudinally to receive and retain the inner end 16 of the 70 spring 13. At its ends the pivot-member is provided with pintles 17 and 18, which are seated in perforations in the ears 6 of the face-plate, and fastened therein by upsetting their ends, as shown in Fig. 2. The pinte 75 17 forms also a bearing for the web 9 of the pulley. As this bearing is comparatively narrow and is located entirely at one side of the band 12, it will be apparent that the pull of the band upon the pulley tends to 80 move the pulley angularly upon its bearing. This movement is prevented, however, by the engagement of the flange 11 with the edge of the pulley-casing, and in this manner a certain amount of friction is produced 85 proportionate to the tension of the band. The mechanism acts, therefore, in an automatic manner to provide the necessary friction to prevent the balance from raising the sash freely.

90 To prevent the pivot-member from rotating the pinte 18 is provided with a widened portion 19 having flat lateral surfaces, and this part 19 fits within an opening of corresponding form in the part 7 of the pulley-casing. Since the pulley-casing is prevented from rotation by engagement of its front extremity with the face-plate, the pivot-member is thus securely locked against rotation, so as to provide a firm anchorage for 100 the inner end of the spring 13.

95 The construction just described facilitates the manufacture of the sash-balance, particularly with respect to the pulley and the pulley-casing, since it permits these parts to 105 be formed of sheet-metal, without any axial sleeves or extensions to provide bearing-members or an anchorage for the spring,

both these functions being combined in the independent pivot-member above described.

We claim:—

In a sash-balance, the combination, with a face-plate having rearwardly-projecting lateral ears, a pulley-casing mounted between said ears, a pulley located within the pulley-casing and having a lateral web portion and a rim, and a coiled spring 5 closed within the pulley and connected thereto at its outer end, of a pivot-member extending through said ears, said pulley-casing, and said pulley, and comprising pintles seated in said ears, and a central en-

larged portion constituting an anchorage for 15 the inner end of the spring, one of said pintles forming a bearing for the web-portion of the pulley, and the other pintle having a non-circular portion, and the pulley-casing having a non-circular opening embracing 20 said non-circular portion and preventing rotation of the pivot-member.

GEORGE J. MACLAUGHLIN.
JAY L. WILLARD.
